HERMETIC SEAL FOR LIGHT-SENSITIVE MATERIAL

Cyril S. Treacy, Scarsdale, N. Y., assignor to
United Research Corporation, Long Island
City, N. Y., a corporation of Delaware

Application April 16, 1935, Serial No. 16,578

4 Claims. (Cl. 201—63)

This invention relates to a light sensitive cell and the method of constructing the same, and is in the nature of an improvement of an element of the cell construction shown in an application of Carpenter and Ross, Serial No. 747,610 filed October 9, 1934, which has matured into Patent No. 2,041,816, in which the complete assembly is disclosed and claimed.

An object of the present invention is to provide a more efficient hermetic seal for the protection of the selenium used in a light sensitive cell. Selenium being subject to variations in moisture, it becomes important to hermetically seal the active portion of the cell in an operative position and still retain its relative proportions as disclosed in the above-mentioned application.

The manner in which this is accomplished will be apparent from the following description and accompanying drawing wherein:

20 Fig. 1 is a perspective view of a light sensitive cell assembly.

Fig. 2 is a plan section taken in a plane along line 2—2 of Fig. 1.

Fig. 3 is a sectional elevation taken in a plane 25 along line 3—3 of Fig. 2; and

Fig. 4 is an enlarged detail view taken along the line 4—4 of Fig. 3 and showing the interdigitated electrodes.

Referring now to the details of the drawing in which like numerals indicate like elements, a light sensitive cell 1 has a base member 2, which is preferably formed of porcelain, isolantite, "Bakelite", or other suitable insulating material. A recess 3 is provided in one side of the base 2 35 to receive an electrode assembly generally indicated at 4. The assembly 4 includes a transparent base plate 5, such as glass, on the rear side of which is plated or fused a coating of hard metal 6, generally an alloy of platinum or palladium, for example, as disclosed in the patent to

30 Carpenter, No. 1,940,245. Over the metal 6 another coating 7 and 7' of a softer metal such as silver is placed, as shown in Fig. 3, to provide a base on which wires 8 and 9 may be soldered.

45 After the layer 6 has been deposited on the surface of the glass plate 5, it is separated into two sections or electrodes 10 and 10' by tracing a sinuous path 11 thereon to form a series of interdigitated projections 12 and 13 as will be seen in Fig. 4. A thin layer of selenium 14 or other light sensitive material is then deposited on the face of the metal 6 to bridge the gap formed between the two electrodes 10 and 10'. This is usually 50 accomplished by sublimation, that is, by vaporiz-

ing the light sensitive material from a solid and allowing it to condense upon the metal 6.

To protect the selenium surface a cup-shaped piece of glass 15 is placed thereover at the rear surface of the metal layer 6. This glass cap is 5 sealed to the metal surface by a cementing wax 18. In this particular feature my cell construction differs from that referred to in the above-identified application and is an improvement 10 thereover from the standpoint of structural design which provides an improved seal. It is very desirable to produce under the glass cap a partial vacuum and this is accomplished by heating the glass member 5 and the cap to a temperature 15 above the melting point of the wax, and as the cap is held tightly upon the metal surface, the wax is applied at the contact edge between the surface and cap and fills the recess groove 17 so provided. When this assembly cools a partial 20 vacuum is created under the glass cap and around the selenium and there is therefore a certain pressure produced on the cementing material.

To prevent the sealing material, which is melted to a liquid when applied to the cap, from entering the chamber and thus covering a portion of 25 the active surface, the cap is provided with a single ring contact surface which may be more firmly fitted to the surface than a double ridged cap or a cap having its contact edge of the same width as its body portion. The large groove formed 30 by narrowing the contact edge also permits sufficient wax to be applied at the optimum position to provide a particularly efficient seal between the cap and the metal surface. This type of cap prevents the cement from seeping under the glass 35 and therefore provides a hermetic seal. To further protect the selenium from moisture, I apply a coating of moisture-proof material 19, such as asphalt, to the electrode assembly 4.

A recess 21 is formed in the base 2 to allow the 40 cup member 15 to be received therein. Also, a pair of vertically disposed grooves 22 and 23 are formed in the top and bottom of the base member 2 to receive the wires 8 and 9. The upper and lower portions of the outer surface of the base 2 45 are also recessed as at 24 and 25 to receive metal caps 26 and 27 which have soldered thereto the wires 8 and 9, as shown at 28 and 29, respectively. It will be seen, therefore, that the caps 26 and 27 50 serve to form contact terminals for the electrodes 10 and 10' as well as to form retainers to hold the assembly in place.

In order to hold the caps 26 and 27 in position, I provide detents (not shown) in the base 2 55

wherein the sides of the caps are indented as at 30 and 31 in Fig. 1.

The cell may be assembled as follows: The lead-in wires 8 and 9 are soldered to their respective electrodes 10 and 10', the wires 8 and 9 at this time being substantially longer than as shown in Fig. 3. The electrode assembly 4 is then placed in the recess 3 and the caps 26 and 27 are fitted into the position shown in Fig. 3, after threading the wires 8 and 9 through the apertures 28' and 29' in the caps 26 and 27 respectively. The caps are then fastened in position by indenting the same at 30 and 31 in Fig. 1 into indentations, not shown, in the base 2, similar indentations, not shown, also being provided in the opposite side of the cell. The wires 8 and 9 are now pulled to bring the electrode assembly 4 in contact with the bottom of the recess 3, as shown in Fig. 3, and the wires 8 and 9 are soldered to the caps 26 and 27, respectively, as shown at 28 and 29, and the surplus portion of these wires 8 and 9 which extends beyond the caps is removed.

Having thus described my invention, what is claimed as new and desired to secure by Letters 25 Patent is:

1. In a light sensitive cell construction, a base plate having a flat surface, interdigitated electrodes on said surface, light sensitive material bridging said electrodes, a hollow cap covering 30 said material, said cap contacting said surface and having a single inner contact edge of smaller thickness than the body of said cap, and cementing material at the contact of said cap and said base plate and underlying the body of said cap.

35 2. A light sensitive cell cover for light sensitive

material deposited on a substantially flat surface comprising a hollow cover cap positioned over said material, said cap contacting said surface and having a single narrower contact portion than body portion with a groove on the external 5 diameter thereof, and a cementing material filling said groove and underlying said body portion.

3. A light sensitive cell construction comprising a transparent plate having a flat surface, electrodes on said flat surface, light sensitive material bridging said electrodes, a hollow cap positioned 10 over and contacting said light sensitive material, said cap having a wall with a single contact edge of lesser width and diameter than the body of the wall of said cap, cementing material positioned 15 in the groove formed by said edge of lesser width, and underlying the major portion of the wall of the body of said cap, and a moistureproof material covering said cap and said cementing material.

4. The method of providing a partial vacuum for the active portion of a light sensitive material deposited on a flat surface within a grooved hollow cap, comprising heating said surface and said cap to a predetermined temperature above the 25 operating temperature of said surface, and hermetically sealing said active portion of said light sensitive material within the chamber by applying at the contact edge between said surface and said cap, with said cap in position, a cementing 30 material which is a solid at the operating temperature of said light sensitive material the partial vacuum being created upon the cooling of said materials.
